UNITED STATES PATENT OFFICE.

FREDERIC E. WELLS, OF GREENFIELD, MASSACHUSETTS.

SCREW-MACHINE.

SPECIFICATION forming part of Letters Patent No. 714,841, dated December 2, 1902.

Application filed June 30, 1902. Serial No. 113,886. (No model.)

To all whom it may concern:

Be it known that I, FREDERIC E. WELLS, a citizen of the United States of America, residing at Greenfield, in the county of Franklin 5 and State of Massachusetts, have invented new and useful Improvements in Screw-Machines, of which the following is a specification.

This invention relates to screw-machines 10 and analogous constructions, and has particular reference to mechanism for operating the tool-turret of such machines, the object of the invention being to provide in this class of machines a turret-feed operated at will in 15 either direction, either by fluid-pressure or interchangeably by a screw-feed, and in the provision of means whereby the turret when operated by fluid-pressure may be so operated at any desired rate of speed, or at one 20 rate of speed in one direction and at a different rate in the opposite direction.

In the drawings forming part of this application, Figure 1 is a longitudinal elevation, partly in section, of a machine embodying 25 my invention. Fig. 2 is an enlarged transverse section on line 22, Fig. 1. Figs. 3 and 4 are perspective views of mechanism whereby the turret and turret-operating devices are operatively connected. Fig. 5 is a trans- 30 verse section through the valve, whereby the flow of fluid to and from the turret-operating devices is controlled.

This invention is particularly applicable 35 and is shown applied to a screw-machine having a cylindrical turret-slide, such as is shown in my patent of November 20, 1900, No. 662,209. In the drawings this turret-slide is indicated by *a* and is suitably supported on the frame of the machine. It is in the form of 40 a hollow cylinder, and the outer end thereof may or may not be supported by a vertical frame, as shown. In machines adapted to small work such support is unnecessary. The turret is indicated by *b* and is in the form of 45 a ring having a hub-like projection *c* thereon, whereby a suitable bearing on the turret-slide is provided, and to this projection the turret-rotating devices are secured. These will be described farther on. At the various 50 points about the periphery of the annular turret at which the tool-chucks are mounted there are formed radially-disposed bosses or

projections *d*, (shown in Fig. 2,) which preferably are integral with the turret and whose outer surfaces are concentric therewith. These 55 tool-chucks are indicated by *e* and are capable of a circumferential adjustment to a slight extent and in their adjusting movement may slide on a circumferentially-disposed gib *f* and are secured to the turret by bolts *g*. 60 The tool-holding element on the stud is herein shown in the form of a split sleeve. This, however, is a mere matter of choice, as the tools may be secured to the chucks in any way found desirable. 65

The turret-rotating devices consist of a wheel *h*, secured to the hub *c* of the turret, and between the hub of this wheel and the end of the hub of the turret there is an annular groove *i*, which is shown in Fig. 1 partly 70 in full lines and partly in dotted lines. On opposite sides of the turret-slide there is a slot *j*, parallel with the axis of the slide, and a cross-head *k* (shown in Fig. 3) is located in said turret-slide transversely thereof, the 75 ends of which project through the slots *j* and into the annular groove *i*, by which connection is made with the turret, of such a nature, however, that while the latter may revolve at will on the turret-slide *a* it may be moved in 80 either direction on said slide by means of this connection with the cross-head. This is apparent by a glance at Fig. 3, which shows the relation of the parts in their operative position. The cross-head *k* within the tur- 85 ret-slide *a* is connected with the turret-feeding devices, as will be hereinafter described. Suffice it for the moment to say that by means of these devices the turret and the wheel *h* are moved longitudinally of the slide. 90

Means for rotating the turret consist in an arm *m*, bolted to the wheel *h* and extending rearwardly therefrom near the surface of the slide. Secured non-rotatably upon the slide there is a sleeve *n*, having on the surface 95 thereof cam-grooves *o* of such contour that when the turret runs backward away from the work and the arm *m* engages one of these cam-grooves *o* the turret will thereby be rotated to a degree equal to half the distance 100 between two of the tool-chucks, and when the turret goes forward again toward the work the other half of its rotational movement will be imparted thereto by the engagement of

the arm *m* with another cam-groove having the proper conformation. To insure the guiding of the arm *m* in the proper direction, there is a swiveled shoe *p* on its end having 5 pointed extremities, as clearly shown in Fig. 1, whereby the proper groove may be engaged to move the turret in the right direction.

The particular form of cam-groove required 10 to give the turret a rotational movement, as above described, is that of the letter **Y**, laid out with the branch ends thereof toward the rear end of the machine and connected together at the ends thereof. Thus when the 15 shoe *p* on the end of the arm *m* enters one of these **Y**-shaped grooves if the shoe has its extremity beveled, as shown in Fig. 1, it will always engage that branch of the **Y**-groove which will carry the turret away from the ob- 20 server as the parts are seen in Fig. 1. If, however, the shoe *p* be reversed, then the back- 25 ward and forward movements thereof in said **Y**-grooves will impart to the turret rotational movement in the opposite direction. Thus far 30 there has been nothing described in this construction which provides for holding the turret against rotation during its operative movement toward and in contact with the work. Such a device, however, is provided for and 35 is shown in side and end elevation in Figs. 1 and 2, and it is constructed as follows: There extends between the standard of the machine and the frame part which supports the outer end of the turret-slide a trough *q*, in which 40 oil and chips which may drop from the machine are caught. On one edge of this trough the metal is thickened sufficiently to permit planing out therein a slideway for mounting therein a plate *r*. The latter is considerably 45 shorter than the slideway in which it moves, and it may be secured therein by screws *s* or otherwise in any desired position. The plate *r* is milled out to receive the guide-bar *t*, which is of substantially the same length of 50 the plate in which it rests and is movable in and out of said slot by means of two arms *u*, pivoted, as shown in Fig. 2, on the plate *r* and engaging by pin-and-slot connection the ends of the bar *t*. The free ends of the arms 55 *u* are united by a rod *v*. Said bar *t* rests on spiral springs *w*, whereby it is pressed out- 60 wardly.

The location of the above-described parts is such that the bar *t* will have a movement 55 radial to the axis of the turret-slide. In the periphery of the wheel *h*, which is attached to the hub *c* of the turret, there are notches *x*, with which the edge of the bar *t* will engage when the turret and the wheel *h* are re- 60 volved, and when so engaged by said bar a tool is brought into proper operative position relative to work held in the chuck *y*. This chuck is mounted on a spindle 2, provided with driving-pulley 3, all as usually con- 65 structed in this class of machine. When the rim of the wheel *h* has been engaged, as just described, by the bar *t*, then the movements

of the turret back and forth on the slide *a* are guided by the engagement of said wheel with said bar. Means are provided—as the screw 70 4, for example—whereby the bar *t* may be securely locked in or out of engagement with the rim of the wheel *h*. The springs *w* will in ordinary usage hold the bar in engagement with the notches in the wheel *h*. In 75 their proper operative relation the plate *r* is so located that the wheel *h* during the forward movement of the turret may not become disengaged from the bar *t*; but upon the movement of the turret in the opposite 80 direction the wheel *h* will run off the end of the bar *t* just after the shoe *p* on the arm *m* has entered the straight portion of one of the cam-slots *o*. Thus the wheel *h* is never free to be revolved by hand on the slide unless 85 the bar *t* is held out of engaging position therewith.

It is obvious that the spacing of the slots *x* about the periphery of the wheel *h* must be identical with the spacing of the tool-chucks 90 *e* about the periphery of the turret.

The feed mechanism for the turret may, as has already been described, be derived from two sources—viz., a screw-feed or a feed operated by fluid-pressure. Fluid-pressure 95 feed for the turret is provided by locating a cylinder 5 in the frame of the machine in axial alignment with the turret-slide and providing therein a piston-head 6, from which there extends through the usual stuffing-box in the 100 end of the cylinder a piston-rod 7, which is screwed into or otherwise secured in a boss 8 on the cross-head *k*, as shown in Figs. 1 and 3. The cylinder is entered at either end thereof by a pipe 9, in which there is located 105 a four-way valve 10. Communicating with this valve is a pipe 12, in which there is located a force-pump 13, the suction end of which by a pipe 14 communicates with a reservoir 15, containing some suitable fluid, 110 as oil or water, which by the operation of the pump is forced through the valve 10 into either end of the cylinder, as desired, the valve 10, of a well-known four-way type, being so constructed that when one end is made 115 to pass under pressure into one end of the cylinder a passage will be opened there-through, whereby fluid in the opposite end of the cylinder may escape through the waste- 120 pipe 16 into said receptacle 15. It is obvious, therefore, that the cylinder 5 will at all times be filled to its full capacity on both sides of the piston-head, whereby great steadiness in the movement of the piston may be attained, and, if necessary, to this end the outlet or 125 waste pipe 16 may be made, if desired, of a slightly-smaller area than the inlet-pipe 12 and the valve-passages. By manipulating the plug of the valve 10 the turret can thus 130 be moved by the means described by the pressure of the fluid against the piston 6 in either direction and at any desired rate of speed. It is desirable, however, at times for certain classes of work that the turret should

be provided with a screw-feed, and to this end the piston 6 and the piston-rod 7 are provided with an axial passage therethrough, and a long feed-screw 17 passes through the cylinder, the piston-head, and the piston-rod and also through the cross-head *k* to the outer end of the turret-slide, at which point it may be rotatably supported. Only so much of the outer end of the feed-screw need be threaded as is requisite to carry the turret to and from the work the required distance. Where this feed-screw enters the cylinder and enters the piston-head 6 suitable packing-glands 18 are provided to prevent the leak of oil through the piston-rod 7. Enough oil, however, will reach that part of the feed-screw lying within the piston-rod to provide for its proper lubrication. The end of the feed-screw which projects through the head of the cylinder 5 at the end of the machine is connected by suitable gears 19 with the spindle 2 in the same way that such connections are made on other machines of this class for driving a feed-screw. At that point where the feed-screw comes through the cross-head *k* there is provided means, which are illustrated in Fig. 3 and also on a smaller scale in Fig. 2, whereby the cross-head may be locked to the feed-screw by the engagement with the latter of a nut carried on the cross-head. This nut construction is shown in said Fig. 3 with the parts in separated relation. The construction is as follows: There is cast on the cross-head *k* a vertically-disposed plate 20, in which the horizontal groove 21 is planed out, which lies at right angles to the feed-screw. In this groove the plate 22 may slide toward and from the feed-screw to cause the engagement with the latter of a nut 23 on said plate 22. This plate may be confined in the groove 21 in any suitable way, as by screwing a strip along each edge of the plate 20, the edges of which shall overlap the edges of the plate. To throw the nut 23 into or out of engagement with the feed-screw, an ear 24 is cast on the plate 22, and another ear 25 is cast on the cross-head, and when the plate 22 is in its proper position these two ears are in alignment, and the screw-threaded end of a pin 26 enters a similarly-threaded hole in the ear 24, the opposite end of the pin projecting through the ear 25 and being provided with a suitable head whereby it may be rotated. A collar 27, fixed on the said pin 26, or a flange turned thereon lies between the ears 24 and 25, and thus prevents endwise movement of said pin in one direction, and the head of the pin applied thereto outside of the ear 25 likewise prevents endwise movement of the pin in the opposite direction. Thus the plate 22 may be moved up against the feed-screw with any desired degree of force and may be withdrawn from contact therewith at will. The feed-screw would be used generally to drive the turret toward the work only and could not be utilized for the reverse movement of the turret unless means were provided for reversing its rotative movement. Its principal use, however, in connection with this class of machines is for imparting to the turret a known feed movement relative to the rotation of the work whereby certain screw-threads may be cut as desired. For other work the fluid-pressure feed is to be preferred, and by throwing the nut 23 out of engagement with the feed-screw the fluid-pressure feed may be used exclusively.

Having thus described my invention, what I claim, and desire to secure by Letters Patent of the United States, is—

1. In a screw-machine, a tool-turret, a turret-slide, a feed-screw for the latter, and devices for connecting and disconnecting the turret and feed-screw; a cylinder, and piston therein, within which said feed-screw is axially located, a tubular piston-rod, through which the feed-screw extends, secured by one end to the turret, and devices for supplying fluid under pressure to said cylinder to move the turret independently of said feed-screw.

2. In a screw-machine, a cylindrical turret-slide, an annular tool-turret longitudinally and rotatably movable on the slide, a feed-screw for moving the turret, and devices for connecting and disconnecting the latter from the feed-screw; combined with other turret-feeding devices comprising a cylinder, a piston therein, a tubular piston-rod through which said feed-screw extends, said rod being secured by one end to the turret, and devices for supplying fluid under pressure to said cylinder to move the turret independently of the feed-screw.

FREDERIC E. WELLS.
